LEONARD J. MARSHALL, OF WESTWOOD, NEW JERSEY, ASSIGNOR TO INTERNATIONAL COMBUSTION ENGINEERING CORPORATION, OF NEW YORK, N. Y., A CORPORATION OF DELAWARE

BENT-TUBE BOILER

Application filed March 21, 1929. Serial No. 348,807.

This invention relates to bent tube boilers such, for example, as a Stirling boiler having upper steam and water drums and a lower mud drum.

5 One of the primary objects of the invention is to provide a boiler of this type which may be operated at high rates without encountering difficulties with wet steam.

Another object of the invention is to provide a boiler of this type which can be operated under relatively high pressure, but in which relatively large thin-walled, and, therefore, relatively, inexpensive steam and water drums may be employed.

15 More specifically, it is an object to provide a boiler of this type in which relatively large, riveted steam and water drums may be employed.

My invention also contemplates a novel arrangement for connecting the tubes whereby ample ligaments may be provided.

20 How the foregoing, together with such other objects and advantages as may hereinafter appear, or are incident to the invention, are realized is illustrated in the accompanying drawings, wherein—

Fig. 1 is a vertical section through a boiler embodying my improvements.

Fig. 2 is a section on the line 2—2 for the 30 purpose of illustrating the tube arrangement, and

Fig. 3 is a fragmentary view on an enlarged scale illustrating the development of one of the steam and water drums.

35 Referring now to the drawings, the reference numeral 7 indicates the mud drum and the reference numerals 8 and 9 the upper steam and water drums. The steam and water drums and mud drum are connected by three banks of tubes A, B and C.

The front bank A, horizontally considered, preferably consists of rows of tubes 10—11, 10—11, etc. across the width of the bank, each row being preferably five tubes deep, with the tubes in each row in alignment with one another. The tubes of the rows 10 are expanded into the drum 8 in a region above the region at which the tubes of the rows 11 are expanded into such drum.

40 The bank B is similarly composed of rows

12—13, 12—13 across the width of the boiler, these rows being preferably six tubes deep. The first three tubes 13a of each row 13 are connected to the steam and mud drum 8 and the last three tubes 13b are bent rearwardly and upwardly for connection with the steam and water drum 9.

The first four tubes 12a of each of the rows 12 are bent slightly to the rear at the top for connection with the steam and water drum 8 in a region to the rear of the region at which the tubes 13a are connected.

The last two rows 12b of each row 12 are bent rearwardly and upwardly for connection with the steam drum 9 in a region below the region at which the tubes 13b are connected thereto. The water circulators 14 connecting the two drums 8 and 9 are connected to the respective drums in a region to one side of the region at which the tubes 12a are connected, and in a region to one side of the region at which the tubes 13b are connected.

The tubes of the bank C are arranged in aligned rows 15 and 16, each row being preferably five tubes deep. The tubes of the rows 15 are bent forwardly and upwardly for connection with the steam and water drum 9 in a region to one side of the region at which the tubes of the rows 16 are connected to said drum.

50 Steam circulators 17 are provided between the two drums.

It will be seen from the foregoing arrangement that ample ligaments are provided for all of the tubes connected to the drums 8 and 9, in consequence of which I am enabled to use large steam and water drums and to make them of relatively thin walled construction. I may also employ a riveted drum construction for these steam and water drums, even though relatively high pressures are employed, say, for example, 600 pounds or thereabout. By the ability to employ large thin-walled drums the construction is less expensive than would otherwise be the case, and, in addition, the large drums will afford not only a large reservoir for water, thereby securing adequate water supply, but also large steam re-

leasing surfaces with correspondingly large steam space above the water line.

There is, thus, the effective steam release and a minimizing of difficulties in connection with wet steam.

5 The arrangement is also one in which proper water levels will be maintained in the two steam and water drums.

10 In the arrangement shown the steam and water drums are approximately 54 inches in diameter and the mud drum 42 inches in diameter. The walls of the steam and mud drums are 2 inches thick.

15 The steam is preferably taken from the rear steam and water drum.

I claim:—

1. In combination, a bent tube boiler having a plurality of relatively large thin walled steam and water drums, a mud drum, 20 and connecting banks of tubes, each bank consisting of non-staggered tubes, every alternate row of the first bank being connected to the first steam and water drum in a different region than the other rows circumferentially of the drum, and every row of 25 the second bank having part of its tubes connected with the first and part with the second steam and water drum but with alternate rows connected to said drums at different regions circumferentially from the other rows thereof, and the alternate rows of the third bank being connected with the second drum at regions circumferentially different from the other rows thereof.

30 2. In combination, a bent tube boiler having a plurality of relatively large thin walled steam and water drums, a mud drum, and connecting banks of tubes, each bank consisting of non-staggered tubes, every alternate row of the first bank being connected to the first steam and water drum in a different region than the other rows circumferentially of the drum, and every row of 35 the second bank having part of its tubes connected with the first and part with the second steam and water drum but with alternate rows connected to said drums at different regions circumferentially from the other rows thereof, and the alternate rows of the 40 third bank being connected with the second drum at regions circumferentially different from the other rows thereof, together with water circulation tubes between the steam and water drums connected thereto in regions above those at which boiler tubes are 45 connected thereto.

3. In combination, a bent tube boiler having a plurality of relatively large thin walled steam and water drums, a mud drum, and 50 connecting banks of tubes, each bank consisting of non-staggered tubes, every alternate row of the first bank being connected to the first steam and water drum in a different region than the other rows circumferentially of the drum, and every row of 55

the second bank having part of its tubes connected with the first and part with the second steam and water drum, but with alternate rows connected to said drums at different regions circumferentially from the other rows thereof, and the third bank having its tubes connected with the second drum at regions circumferentially different from the regions at which the tubes of the second bank connect.

4. In combination, a bent tube boiler having a plurality of steam and water drums, a mud drum, a front bank of tubes connecting the mud drum with the first steam and water drum, a second bank consisting of non-staggered tubes every row of which has part of its tubes connected with the first and part with the second steam and water drum but with alternate rows connected to said drums at different regions circumferentially from the other rows thereof, and the third bank of tubes connecting the mud drum with the second drum.

5. In combination, a bent tube boiler having a plurality of steam and water drums, a mud drum, and connecting banks of tubes including a second bank every row of which has part of its tubes connected with the first and part with the second steam and water drum but with alternate rows connected to said drums at different regions circumferentially from the other rows thereof.

6. In combination, a bent tube boiler having a plurality of steam and water drums, a mud drum, and connecting banks of tubes including a second bank every row of which has part of its tubes connected with the first and part with the second steam and water drum but with alternate rows connected to said drums at different regions circumferentially from the other rows thereof, and the tubes of the remaining banks being connected into the first and second steam and water drums at regions circumferentially different from the regions at which the tubes of the second bank connect.

In testimony whereof I have hereunto signed my name.

LEONARD J. MARSHALL.
